UNITED STATES PATENT OFFICE

2,530,073

AUTOMATIC CONTROL FOR STEAM
BOILERS OR TANKS

Charles L. Oliver, Portsmouth, Va.

Application January 9, 1948, Serial No. 1,348

5 Claims. (Cl. 122—451)

1

This invention relates to a system for automatically controlling the steam pressure in a tank or boiler and for automatically replenishing the water therein when the level thereof falls below a predetermined point.

More particularly, it is an object of the present invention to provide a system of the aforescribed character wherein an excess of steam pressure in the tank or container will be utilized for pumping a liquid for replenishing a low liquid level in the container thereby dissipating an excess of steam pressure and replenishing the supply of liquid in the container simultaneously for maintaining the container or tank under the most desirable condition.

Another object of the invention is to provide a system of the aforescribed character wherein a steam pump may be utilized in lieu of an electric pump with considerable saving in installation and maintenance cost and with a maximum saving in operating cost due to the fact that an excess of steam pressure is utilized for operating the steam pump.

Still a further and important object of the invention is to provide a system wherein through an electric circuit and control switches operative in response to conditions within a boiler or container, said system may be automatically utilized for replenishing the supply of liquid in the container and for simultaneously dissipating an excess of steam pressure therein or for merely replenishing the supply of liquid where an excess of steam pressure does not exist.

A further object of the invention is to provide a system of the aforescribed character of extremely simple construction capable of being economically manufactured and sold and which will function efficiently for accomplishing its intended purposes and which will require substantially no maintenance or supervision.

Another object of the invention is to provide a system of the aforescribed character capable of being utilized with steam boilers or tanks where a high voltage supply of electricity, such as is required for operating an electric motor is not available and accordingly where a system utilizing an electric motor actuated pump for replenishing the liquids in a tank or boiler could not be employed.

Various other objects and advantages of the invention will hereinafter become more fully apparent from the following description of the drawings, illustrating a presently preferred embodiment thereof, and wherein:

Figure 1 is a diagrammatic view showing the 55 system connected to a steam boiler or tank;

2

Figure 2 is an enlarged sectional view, partly in side elevation, of one of the switches utilized in the electric circuit of the system, and

Figure 3 is a similar view of the other switch of said electric circuit.

Referring more specifically to the drawings, and first with reference to Figure 1, the numeral 5 designates generally a conventional steam boiler or tank, only a part of which is illustrated, and with which the novel control system, designated generally 6 and constituting the invention is adapted to be utilized.

The boiler or tank 5 is provided with vertically spaced liquid level tubes 7 and 8 having remote ends communicating with the chamber of the boiler or tank 5 and adjacent ends communicating with the housing 9 of an electric switch, designated generally 10 and which is operated by the liquid level in the tank 5. Two conductor 11 and 12 lead from a suitable source of electric supply, not shown, such as a 110 volt electrical outlet and the conductor 11 connects with one terminal of the switch 10 and the conductor 12 leads to and connects with a part of a switch, designated generally 13 and also forming a part of the control system 6. Another conductor 14 leads from the other side of the switch 10 to another part of the switch 13, as will hereinafter be described and as illustrated in Figure 2, and it will be readily obvious that if required a relay may be interposed in the conductors 12 and 14 between the switch 13 and the liquid level actuated switch 10 and electric source.

The tank or boiler 5 has a steam supply conduit or pipe 15 extending from the dome thereof for supplying steam from said tank or boiler to any suitable mechanism or machinery to be operated thereby, not shown. A steam supply conduit or pipe 16, forming a part of the automatic control system 6 is connected to the steam line 15 for receiving steam under pressure therefrom and it will be readily apparent that the pressure of the steam in the conduit 16 will be substantially equal to the steam pressure in the pipe 15 or in the upper part of the boiler 5.

The control system 6 includes a steam engine 17 for operating a steam pump 18. A steam supply conduit 19 communicates with the steam engine 17 and is adapted to supply steam thereto for operating the steam engine and pump and is in turn connected, intermediate of its ends, to the opposite, laterally extending end 20 of the conduit 16. The conduit portion 20 is provided with a strainer 21 and between said strainer and the conduit 19, said conduit portion 20 is provided with a conventional type of shutoff valve 22 which

is controlled by a solenoid 23 which may likewise be of any conventional construction. The conduit 16 is provided with a branch passage or pipe 24 which connects with the opposite end of the conduit 19 and between said passage 24 and the valve 22, a manually regulated shutoff valve 25 is provided in the conduit 16. The conduit 19 is also provided with a manually regulated shutoff valve 26 interposed therein between the conduit portion 20 and the passage 24.

A pipe 27, provided with a loop and of a much smaller diameter than the conduits previously referred to communicates with the conduit portions 19 and 24 at their junction and has an opposite end connected to and communicating with a pipe 28 to one end of which is connected a pressure gauge 29 for indicating the steam pressure in the conduit 16 and the portion of the conduit 19 disposed above the valve 26.

The opposite end of the pipe 28, as best illustrated in Figure 2, extends through the housing 29 of the switch 13 and is connected to and communicates with a steam responsive bellows 30, disposed within said housing 29 and forming a part of the switch 13.

The pump 18 is provided with a conduit 31 which opens into the intake side thereof and the opposite end of which, not shown, may be connected to any suitable source of water supply, preferably a condensate tank. The pump 18 is provided with a conduit 32 leading from and communicating with the discharge thereof and having a discharge end opening into the boiler 5. A pipe or conduit 33 leading from a source of water supply under pressure, such as a city water supply connects and communicates with the conduit 32 adjacent the end thereof which discharges into the boiler 5 and said conduit 32 is provided with a check valve 34 disposed between its connection with the pipe 33 and the pump 18 and which is arranged to open only to permit the passage of water from the pump 18 therethrough in a direction toward the boiler 5 and so that water from the water main conduit 33 can not flow through the conduit 32 toward the pump 18. The conduit 33 is provided with a normally closed valve 34a, corresponding to the valve 22 and which is adapted to be opened by a solenoid 35, when energized, and which corresponds to the solenoid 23. A check valve 36 is interposed in the conduit 33 between the valve 34a and its connection to the pipe 32 and is likewise constructed and arranged to prevent flow of water through said conduit toward the valve 34a but to permit the flow of water therethrough toward the conduit 32.

The liquid level responsive switch 10 may assume any desired form so long as it will function to assume a circuit closing position when the liquid level in the boiler 5 falls below a predetermined point. As illustrated in Figure 3, said switch 10 may include, in addition to the housing 9, a float 37 having a stem 38 extending upwardly therefrom and which extends reciprocally through a stuffing box 39 in a top wall 40 of the float housing 9. It will be readily obvious that the liquid level in the housing 9, as indicated at 41 in Figure 3, will be the same as the liquid level in the boiler 5 and that the level of the float 37 relatively to the housing 9 will vary and be governed by the liquid level 41. The upper portion of the float stem 38 extends into a chamber defined by a housing 42 which is detachably mounted on the housing 9 and which contains a fixed contact 43 which is shown connected to

the conductor 14 and a yieldable contact 44 which is shown connected to the conductor 11. The free end of the yieldable contact 44 is disposed above the fixed contact 43 and is ordinarily retained, by its resiliency, out of engagement therewith. The float stem 38 is provided with a transversely extending arm 45 at its upper end having a depending projection 46 which is normally disposed over and out of engagement with the free end of the yieldable conductor 44. Accordingly, as the liquid level 41 falls within the housing 9 the float 37 will move downwardly therein causing the stem 38 to move downwardly through the stuffing box 39 until the projection 46 engages the free end of the yieldable contact 44 and further downward movement of the float 37 will cause said free end of the contact 44 to be forced downwardly by the projection 46 and into engagement with the contact 43 for closing the electric circuit of the switch. Similarly, when the liquid level 41 again rises the float 37 will move upwardly thereby causing the projection 46 to move out of engagement with the contact 44 so that the latter may by its resiliency return to its position of Figure 3 for interrupting the circuit between the conductors 11 and 14.

Referring to Figure 2, the switch 13 includes a platform or support 47 which is journaled by a bearing 48 on a shaft 49 which extends horizontally through and is supported by the housing 29. A mercury switch 50 is fixedly supported on the platform 47. The switch 50 may be of any conventional construction including an elongated closed container 51 which is partially filled with mercury, as indicated at 52 and which is provided at each end thereof with two electrical contacts including the contacts 53 and 54 which extend into one end of said container 51 and the contacts 55 and 56 that extend into the opposite end thereof. The contacts 53 and 54, and 55 and 56 are disposed out of engagement and a circuit therebetween is closed by the mercury 52 when in engagement with both of the contacts of either pair of contacts. A contractile coiled spring 57 is connected at one end thereof by fastening means 58 to one end of the platform 47 and extends upwardly therefrom and is attached at its opposite end to an adjusting screw 59 which extends through a threaded opening 60 in the top wall of the housing 29 and by means of which the tension on the spring 57 can be varied. The spring 57 functions to normally hold the support or platform 47 tilted as illustrated in Figure 2 and so that the end thereof which is connected to the spring 57 will be held in an elevated position. The bellows 30 has a stem 61 projecting from its upper end and which bears against the under side of the support 47 adjacent the opposite end thereof and on the opposite side of the pivot 49 so that when said bellows 30 is expanded by steam pressure it will cause the support or platform 47 to rock counterclockwise, as seen in Figure 2 sufficiently so that the mercury 52 will flow to the opposite end of the container 51 for completing an electrical connection between the contacts 53 and 54.

The conductor wire 14 extends from the switch contact 43 into the housing 29 and has separate branch portions 62 and 63 which connect with the contacts 54 and 56, respectively. The conductor 12 likewise extends into the housing 29 and connects with one contact post 64 of a conductor strip 65 and has a branch conductor element 66 which connects with a similar contact post 64 of a second conductor strip 67 which is

insulated from the conductor strip 65. Each of the conductor strips 65 and 67 is provided with two contact posts 64 and said strips form electrical connections between the posts 64 thereof. A conductor 68 extends from the other post 64 of the strip 65 and connects with one of the contacts of the solenoid 23 and a conductor 69 extends from the other post 64 of the contact strip 67 and connects with one contact or terminal of the solenoid 35. A conductor 70 connects the mercury switch contact 53 with the other terminal or contact of the solenoid 23 and a conductor 71 connects the contact 55 with the other contact of the solenoid 35.

From the foregoing it will be readily apparent that when the switch 10 is in an open position the electric circuit from the electric source connected to the conductors 11 and 12 will be inoperative so that the solenoids 23 and 35 will be deenergized so that valves 22 and 34a will remain in closed positions. If the steam pressure in the boiler or tank 5 is below a predetermined point, for example, thirty pounds, said steam pressure will be insufficient to expand the bellows 30 sufficiently for rocking the mercury switch 50 from its position of Figure 2 and into a position so that the mercury 52 will close the connections between the contacts 53 and 54, due to the strength of the spring 57. Accordingly, with the system in this condition and if the water level drops sufficiently in the boiler 5 and switch housing 9 to cause the contact 44 to engage the contact 43, as previously described, a circuit will be closed to the solenoid 35 due to the fact that the contacts 55 ad 56, as seen in Figure 2, will be electrically connected by the mercury 52 so that the current will flow from the conductor 11 through the contacts 44 and 43 and conductor 14, through conductor 63 and the contacts 56 and 55 connected by the mercury 52 to and through the conductor 71 to the solenoid 35 and back through the conductor 69, conductor strip 67 and conductor 66 to the negative conductor 12 which is grounded at the electric source. This will energize the solenoid 35 to open the valve 34a so that water from the conduit 33 can flow through the valve 34, past the check valve 36 and through a portion of the conduit 32 into the boiler 5 for replenishing the supply of water therein and raising the water level until the switch 10 is returned to an open position, as previously described.

Should the steam pressure in the dome of the boiler 5 be above the desired pressure, thirty pounds, at the time that the switch 10 is closed the mercury switch 50 will have been previously tilted so that the mercury therein will be out of engagement with the contacts 55 and 56 and electrically connecting the contacts 53 and 54. This results because the pressure in the conduits 15 and 16 is substantially equal to the pressure in the boiler 5 causing a corresponding pressure in the pipes 27 and 28 and accordingly in the bellows 30 and which is sufficient to overcome the resistance of the spring 57 to rock the support 47 and mercury switch 50 to the position, just previously mentioned. Accordingly, when the switch 10 is closed by falling of the water level in the boiler 5 the electric circuit from the conductor 14 will be through the conductor 62, contact 54, mercury 52 to contact 53 and from said contact 53 to the solenoid 23 through conductor 70. Likewise, the solenoid 23 will be grounded through the conductor 68, conductor strip 65 back to the conductor 12 so that the solenoid 23 will be energized for opening the valve 22. When

this occurs, and assuming the valve 25 to be in an open position and the valve 26 to be closed, steam from the conduit 16 will pass through conduit 19 to operate the steam engine 17 which in turn operates the pump 18. This will cause water to be pumped from the condensate tank or other source, not shown, connected to the conduit 31, through pump 18 and conduit 32 into the boiler 5 thus replenishing the liquid in the boiler and at the same time dissipating an excess steam pressure. It will be readily apparent that the mercury switch 50 might reverse the circuit from one solenoid to the other while the boiler or tank 5 is being refilled in the event that the steam pressure diminishes below or increases to above the predetermined point.

The valve 25 can be shut off to prevent operation of the steam engine 17, as for the purpose of cleaning the strainer 21 and said steam engine may be controlled manually by opening the normally closed valve 26 to allow the steam from conduit 16 to pass through the by-pass 24 into and through the conduit 19 to the steam engine.

Various modifications and changes are contemplated and may obviously be resorted to, without departing from the spirit or scope of the invention as hereinafter defined by the appended claims.

I claim as my invention:

1. An automatic control system for steam boilers comprising an electric circuit connected to a source of electric current, a liquid level responsive switch adapted to be actuated by the liquid level in a steam boiler or tank for closing the switch when the liquid level falls below a predetermined point and for opening the switch when the liquid level rises to above said point, said switch being interposed in the electric circuit, a steam pump adapted to be connected to a source of liquid supply and to said boiler for pumping the liquid from said source of supply into the boiler, a steam engine for operating said pump, a steam line connected to the boiler and to said steam engine, a first normally closed solenoid valve for closing said steam line to prevent operation of the steam engine and pump, a conduit leading from a source of water supply under pressure and connected to the boiler or tank, a second normally closed solenoid valve interposed in said last mentioned conduit, a multiple switch connecting each of said solenoid valves independently to said electric circuit, said multiple switch being normally disposed in a position for closing a circuit to the second solenoid valve when said circuit is energized, and a pressure responsive means operatively connected to said multiple switch and to said steam line by a portion thereof which by-passes the first solenoid valve for actuating said multiple switch when the steam pressure is above a predetermined point for interrupting the circuit to the second solenoid valve and for electrically connecting the first mentioned solenoid valve to said electric circuit.
2. An automatic control for steam boilers or tanks comprising an electric circuit connected to a source of electric current, a liquid level responsive switch for controlling said circuit and connected to and adapted to be actuated by the liquid level in a boiler or tank for closing the electric circuit when the liquid level falls below a predetermined point and for opening said circuit when the liquid level rises to above said point, a conduit connected to a source of water supply and to said boiler, and a normally closed

solenoid valve interposed in said conduit and connected to said electric circuit to be energized thereby when the switch is closed for automatically supplying water to the boiler or tank, means adapted to be connected to the boiler or tank and to a second source of water supply for pumping from said second water supply source to refill the boiler or tank, a steam line connecting said means to the boiler or tank, a normally closed solenoid valve interposed in said steam line, and a steam pressure responsive switch interposed in said electric circuit and connected to the steam line and to each of said solenoids for interrupting a circuit to the first mentioned solenoid and for energizing the last mentioned solenoid when said liquid level switch is closed and when the steam pressure in the tank or boiler is above a predetermined point.

3. An automatic control for steam boilers or tanks comprising an electric circuit connected to a source of electric current, a liquid level responsive switch for controlling said circuit and connected to and adapted to be actuated by the liquid level in a boiler or tank for closing the electric circuit when the liquid level falls below a predetermined point and for opening said circuit when the liquid level rises to above said point, a conduit connected to a source of water supply and to said boiler, and a normally closed solenoid valve interposed in said conduit and connected to said electric circuit to be energized thereby when the switch is closed for automatically supplying water to the boiler or tank, means adapted to be connected to the boiler or tank and to a second source of water supply for pumping from said second water supply source to refill the boiler or tank, a steam line connecting said means to the boiler or tank, a normally closed solenoid valve interposed in said steam line, and a steam pressure responsive switch interposed in said electric circuit and connected to the steam line and to each of said solenoids for interrupting a circuit to the first mentioned solenoid and for energizing the last mentioned solenoid when said liquid level switch is closed and when the steam pressure in the tank or boiler is above a predetermined point, and adjustable means associated with said steam pressure responsive switch for varying the amount of steam pressure required for interrupting the circuit to the first mentioned

solenoid valve and for closing the circuit to the last mentioned solenoid valve.

4. An automatic control for steam boilers comprising an electric circuit adapted to be connected to an electric source, a liquid level responsive switch interposed in said circuit and adapted to be actuated by the liquid level in a boiler for energizing said circuit when the liquid level falls below a predetermined point, a conduit for supplying water under pressure to the boiler, a first solenoid valve interposed in and normally closing said conduit, means for pumping water from a source of supply to the boiler or tank, said means being steam operated, a second conduit connected to the boiler and to said means for supplying steam thereto, a second normally closed solenoid valve in said second conduit, and a steam pressure responsive switch connected to said second conduit and interposed in the electric circuit and normally positioned for closing a circuit to said first solenoid valve when the liquid level responsive switch is closed and adapted to be actuated by an excess steam pressure for de-energizing said first solenoid valve and for energizing the second solenoid valve.

5. An automatic control as in claim 4, and manually controlled means for regulating said steam pressure responsive switch to vary the steam pressure required to cause said switch to de-energize the first solenoid valve and to energize the second solenoid valve.
